[57] **CLAIM**

The ornamental design for a suspended spotlight assembly, as shown and described.

DESCRIPTION

FIG. 1 is a perspective view of a suspended spotlight assembly showing our new design;

FIG. 2 is a side elevational view thereof;

FIG. 3 is a bottom plan view thereof;

FIG. 4 is an end view thereof; and,

FIG. 5 is a front view of one of the spotlights, the remainder of the assembly being omitted for convenience of illustration.

FIG. 1

FIG. 2

FIG. 3

FIG. 4

FIG. 5
